Primary Examiner — David Muller(74) *Attorney, Agent, or Firm* — QuickPatents, Inc.; Kevin Prince(57) **CLAIM**

I claim the ornamental design for a reversible pet bed, as shown and described.

DESCRIPTION

FIG. 1 is a perspective view of a reversible pet bed, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a perspective view thereof, illustrated in an inside-out configuration; and,

FIG. 9 is a perspective view thereof, illustrated in an uncinched configuration.

The two contrasting shading patterns used in the figures represent contrasting colors of the fabrics of the design.
